(57) **CLAIM**

We claim the ornamental design for an optical reading device, as shown and described.

DESCRIPTION

FIG. 1 is a top perspective view of an optical reading device. FIG. 2 is a top view of the optical reading device shown in FIG. 1.

FIG. 3 is a bottom view of the optical reading device shown in FIG. 1.

FIG. 4 is a first side view of the optical reading device shown in FIG. 1, the opposite side being a mirror image thereof.

FIG. 5 is a front view of the optical reading device shown in FIG. 1.

FIG. 6 is a rear view of the optical reading device shown in FIG. 1; and,

FIG. 7 is a bottom perspective view of an optical reading device.

The portions shown in broken line are not claimed.
